UNITED STATES PATENT OFFICE.

LLOYD V. LEWIS, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

SPEED-CONTROLLING APPARATUS FOR RAILWAY-VEHICLES.

1,334,385.

Specification of Letters Patent. Patented Mar. 23, 1920.

Original application filed March 12, 1915, Serial No. 13,853. Divided and this application filed January 23, 1918. Serial No. 213,284.

To all whom it may concern:

Be it known that I, LLOYD V. LEWIS, a citizen of the United States, residing at Edgewood borough, in the county of Allegheny and State of Pennsylvania, have invented certain new and useful Improvements in Speed-Controlling Apparatus for Railway-Vehicles, of which the following is a specification.

10 My invention relates to speed controlling apparatus for railway vehicles, and is a division of my co-pending application Serial No. 13853, filed March 12, 1915.

I will describe two forms of apparatus embodying my invention and will then point out the novel features thereof in claims.

In the accompanying drawings, Figure 1 is a diagrammatic view showing one form of controlling apparatus embodying my invention. Fig. 2 is a view similar to Fig. 1 but showing a modification of certain parts of the apparatus shown in Fig. 1. Fig. 3 is a sectional view of a speed responsive device carried on the vehicle and adapted to coöperate with the apparatus shown in Fig. 1 or with the apparatus shown in Fig. 2. Fig. 4 is a plan view showing the relative arrangement of the track rails, ramps and vehicle-carried contact shoes shown in Figs. 1 and 2. 30 Similar reference characters refer to similar parts in each of the several views.

Referring first to Fig. 1, I have here shown one rail 1 of a railway track on which a train or vehicle V is adapted to travel. In order to prevent unnecessary complication of the drawing, I have shown only one wheel 2 of the train or vehicle in rolling contact with rail 1. The train or vehicle V carries the parts shown in full lines in Fig. 1, and 0 also the speed responsive device shown in Fig. 3.

Referring now to Fig. 3, this speed responsive device comprises a casing 3 having a cover plate 8, which casing incloses a centrifugal governor 4, here shown to be of the ordinary fly-ball type, although I do not wish to limit myself to this particular type of governor. Fixed to the shaft 5 of this governor outside of the plate 8 is a pinion 5^a which is operatively connected to one of the wheels of the train or vehicle V by any suitable means, so that the governor is made to rotate at a speed always proportional to the

speed of the train or vehicle. Shaft 5 revolves in a ball bearing 6 located in cover 5^a plate 8 and in a ball bearing 7 located in casing 3. Spider arms 9, extending radially from shaft 5, carry at their extremities bell cranks 10 connected to the spider arms by 60 means of pins 11. One arm 12 of each bell crank carries at its extremity a weight 14, while the other arm 13 of each bell crank extends into a slot 15 in the shaft 5. In slot 15 there is located a shaft 16 provided with 65 two annular shoulders 31 and 32, between which the ball shaped ends of arms 13 of bell cranks 10 are located. The left end of shaft 16 is supported in a hole 16^a in shaft 5, and is capable of longitudinal movement in 70 said hole, while the other end of shaft 16 carries the outer ring 17 of a thrust ball bearing 18. The inner ring 19 of this bearing is fixed to the left extremity of a plunger 20, which is adapted to slide longitudinally in a hole 21 through the head of casing 3. Near its right end plunger 20 is threaded to receive a nut 22 which is locked in position by a lock nut 23. The right extremity of plunger 20 is guided in a hole 25 in a 80 head 26, which head reciprocates in a hole 28 through a plate 29 forming a part of casing 3. The plunger 20 is guided near its left extremity by means of a bushing 24 fixed in casing 3. A stud 33 in shaft 5 is provided as 85 a left hand stop for shaft 16 when the governor 4 is at rest. When the governor revolves, the centrifugal force of the weights 14 is transmitted by means of bell cranks 10 to act as a thrust on bearing 18, and this 90 thrust is transmitted by plunger 20 and nut 22 to head 26, which bears against a diaphragm 341. This diaphragm will then yield unless resisted by an equal or greater force on its other side. I set up this resisting force in the following manner.

An air-tight cylinder 34 closed at one end by means of a head 38 is clamped at its opposite end to the plate 29 so that the axis of the cylinder coincides with the center line 100 of shafts 5 and 20. This cylinder is provided with two pistons 35 and 36 the former of which may be comparatively loose in the cylinder so that air can pass the piston and act directly on the diaphragm 341. A 105 spring 37 is provided to hold these pistons apart, so that piston 35 bears against dia-

phragm 341 and piston 36 normally bears against cylinder head 38. Air pressure from sources to be pointed out later may be admitted to cylinder 34 through ports 39 and 40. By this means I am enabled to oppose or overcome the force exerted by the action of the centrifuge on diaphragm 341. When no air pressure is applied through ports 39 and 40, the spring 37 alone resists the force due to the centrifuge, so that at and above a predetermined low speed the centrifuge overcomes the action of this spring and moves its plunger 20 to the right. When air pressure is applied through port 40, the piston 36 is pushed up against a stop 41, which is cushioned with an annular gasket 42, so that spring 37 is compressed, pushing piston 35 against the diaphragm 341 with a force greater than before. Consequently, the centrifuge 4 may be rotated at a greater speed before it overcomes the force opposing it at the diaphragm and moves plunger 20 to the right. Now, if air at substantially the same pressure is admitted through port 39, piston 36 is forced back against the cylinder head 38, but the force against diaphragm 341 is greater than before, because the air pressure acting directly against the diaphragm more than offsets the decrease in spring pressure caused by allowing the spring to expand. Consequently the centrifuge 4 may be rotated at a still greater speed before the force exerted on diaphragm 341 by head 26 exceeds the force exerted on the diaphragm by the opposing air pressure and by piston 35.

In any event as long as the force exerted on the diaphragm 341 due to the action of the centrifuge is less than the resisting force, head 26 is held against the face 43 of plate 29. When the centrifugal force transmitted to the diaphragm overcomes the resisting force, the diaphragm yields and pushes piston 35 against stop 41.

45 My device may of course be utilized in many different ways to control any desired apparatus on the vehicle; as here shown I use it to control the fluid pressure brakes in the following manner.

50 An arm 45, fulcrumed in casing 3 by a pin 27, is pivoted to plunger 20 by means of a pin 46. The valve stem 49 of a pin valve 44 is operatively attached to arm 45, so that when the plunger 20 moves to the right valve 44, which is normally closed by means of a spring 48, is opened to allow air pressure to exhaust from a pipe 50 through a port 47. Pipe 50 leads to a brake application valve located on the vehicle, which brake application valve may be of any suitable type. Suffice it to point out, that when pipe 50 is opened to atmosphere by valve 44 the brakes of the vehicle are applied, and the brakes are not released until 60 pressure is restored in pipe 50. When dia-

phragm 341 yields to the force due to rotation of the centrifuge and thus allows plunger 20 to move to the right, the balls of the governor fly out to a greater distance from the center of rotation and so increase 70 the centrifugal force even though the speed remains constant. Consequently, if the force exerted by the spring and air pressure remains constant, the speed of the governor must decrease to a value less than 75 the speed which caused the application of the brakes, before the force exerted by diaphragm 341 again overcomes the force due to the action of the centrifuge.

Since governor 4 always rotates at a speed 80 proportional to the speed of the vehicle, the speed of the vehicle is limited by the forces which oppose the force exerted on the diaphragm due to the rotation of the centrifuge. As a concrete example suppose that 85 the apparatus is so proportioned that, when the vehicle travels at the rate of 50 miles per hour, and when air at a pressure of 70 lbs. per square inch is admitted through port 39 to cylinder 34, the forces on the opposite sides of the diaphragm balance each other. Any increase in speed of the vehicle will augment the force due to the centrifuge, whereby the diaphragm will be displaced, valve 44 will be opened, and the 90 brakes will be applied. Due to the increase of radius of the governor balls the brakes remain applied until the speed of the vehicle has been lowered to say 35 miles per hour. Plunger 20 then moves back to the 95 left, valve 44 is closed, pressure builds up in pipe 50 and the brake application valve acts to release the brakes. If air pressure is admitted to cylinder 34 through port 40, and at the same time the air pressure is allowed to exhaust from the middle compartment of cylinder 34, the force acting against the right hand face of diaphragm 341 will be less, so that the speed of the vehicle will be limited to a lower value, say 20 miles per 100 hour. When the air remaining in the cylinder 34 back of piston 36 is exhausted through port 40 the speed of the vehicle will be limited to a still lower value, say 10 miles per hour.

105 For controlling the supply of air to cylinder 34 any convenient apparatus may be used. In Fig. 1 I have shown one form of such control apparatus, which is operatively connected by pipes 120 and 121 with the 110 apparatus described above. This apparatus is adapted for the control of trains consisting of a number of similar cars, each of which is equipped with the apparatus shown in Fig. 1. Four wires 150, 151, 152, 153 are 115 provided for each car, each wire being connected to the corresponding wires of the adjacent cars by means of couplers 154. A battery 155 is permanently connected to wires 150 and 151 by means of wires 156 130

and 157. Contact shoes 162^a and 162^b are located at diagonally opposite corners of the vehicle, so that one of these shoes is always in position to engage a ramp such as 109, a number of which are disposed at intervals on one side of the track rails. A third contact shoe 163 is located on the center line of the car, so that it engages with ramps such as 108, a number of which are placed at intervals midway between the running rails. The relative arrangement of track rails, trackway ramps and vehicle-carried contact shoes is shown in plan view in Fig. 4. Operatively connected to contact shoes 162^a and 162^b are circuit controllers 164^a and 164^b respectively, each having two contact bars 165 and 166 which are carried by but are electrically insulated from a control rod 167 and which bars are adapted to bridge contact points 168—169 and 170—171 respectively. These circuit controllers are biased normally to closed position by means of springs 172 and are opened by means of trips 173 fixed to shoes 162^a and 162^b and arranged to engage rods 167 during the upper portion of the stroke of the shoe. Each car is provided with two relays 158 and 159 responsive to alternating current and with two relays 160 and 161 responsive to direct current. The energizing circuits of relays 158 and 159 are partly on the car and are partly on the roadside. Thus relay 158 is connected to contact shoes 162^a and 162^b by wires 218 and 188 respectively, and to a sliding contact 119 on a car wheel by means of wire 211. Similarly, relay 159 is connected to contact shoe 163 by means of wire 210 and to sliding contact 119 by wire 211.

Ramp 108 may be energized by connecting one terminal of a transformer T to a running rail 1 and connecting the other terminal of transformer T through a circuit controller P to ramp 108. Ramp 109 may similarly be energized from a transformer T' through a circuit controller P'. Hence relays 158 or 159 are energized as long as either contact shoes 162^a or 162^b, or 163 make contact with an energized ramp 109 or 108 respectively. Relay 160 may be picked up by current flowing in the following circuit: from battery 155, through wires 156, 150 and 197, contact 189 of relay 158, wire 191, relay 160, wires 192, 151 and 157 to battery 155. Therefore, in order that relay 160 may be energized, relay 158 must first be energized by current from a ramp 109 as described above. Once relay 160 is energized, however, it will remain energized by current flowing in a stick circuit, which circuit is as follows: from battery 155 through wires 156, 150 and 505, contact bar 166 of circuit controller 164^a, wire 206, contact bar 166 of circuit controller 164^b, wire 209, contact 193 of relay 160, contact finger 221, relay 160, wires 192, 151, and 157 to battery 155. Thus relay 160 remains

energized until its stick circuit is broken by opening either circuit controller 164^a or 164^b. Similarly relay 161 is picked up by current flowing in the circuit: from battery 155 through wires 156, 150 and 197, contact 212 70 of relay 159, wire 213, relay 161 wires 192, 151 and 157 to battery 155. When relay 161 is energized it is held so by current flowing in a stick circuit: from battery 155, wires 156, 150 and 505, contact bar 165 of circuit 75 controller 164^a, wire 214, contact bar 165 of circuit controller 164^b, wire 208, contact 74 of relay 161, contact finger 232, relay 161, wires 192, 151 and 157 to battery 155. Thus relay 161 remains energized until its stick 80 circuit is opened at either circuit controller 164^a or 164^b.

The cab of each car is provided with three signal lights R, Y, G, colored preferably red, yellow and green, respectively. Red lamp R 85 is energized through the circuit: from battery 155, wires 156, 150, 197 and 198, back contact 205 of relay 161, wire 199, back contact 196 of relay 160, wire 200, red lamp R, wires 192, 151 and 157 to battery 155. Thus 90 red lamp R is displayed when both relays 160 and 161 are deenergized. Green lamp G is energized by current flowing through the following circuit: from battery 155, wires 156, 150, 197 and 198, back contact 95 205 of relay 161, wire 199, front contact 195 of relay 160, wire 202, green lamp G, wires 192, 151 and 157 to battery 155. Hence, a green light is displayed when relay 160 is energized and relay 161 is deenergized. The 100 circuit for yellow lamp Y is as follows: from battery 155, through wires 156, 150, 197 and 198, front contact 204 of relay 161, wire 215, yellow lamp Y, wires 192, 151 and 157 to battery 155. Therefore, a yellow light is 105 displayed when relay 161 is energized. From the above arrangement of circuits it is seen that only one light can be displayed at a time. Each car is also provided with two double pin valves 68 and 69, which are biased 110 by springs 82 and 83 to such positions that the lower valves 70 and 71 are closed and the upper valves 72 and 73 are open.

Attached to these valves are valve stems 76 and 77 the upper ends of which are attached to armatures 78 and 79 of electromagnets 80 and 81 respectively. The energizing circuit of magnet 81 is as follows: from battery 155, wires 156, 150, 197 and 198, back contact 205 of relay 161, wire 199, 115 front contact 195 of relay 160, wire 202, energizing winding 81^a of magnet 81, wires 225, 192, 151, and 157 to battery 155. Therefore, magnet 81 is energized when relay 161 is deenergized and relay 160 is energized. 120 The energizing circuit of magnet 80 is as follows: from battery 155, wires 156, 150, 197 and 198, front contact 204 of relay 161, wire 215, winding 80^a of magnet 80, wires 192, 151 and 157 to battery 155. Hence, 130

magnet 80 is energized when relay 161 is energized. It is evident from the above that magnets 80 and 81 cannot be energized simultaneously. When magnet 80 is deenergized, spring 82 holds valve 72 open thus connecting a pipe 120, which leads to port 40 of cylinder 34 in Fig. 3 to atmosphere. When magnet 80 is energized, upper valve 72 is closed and lower valve 70 is opened, thus admitting air pressure from a reservoir 61 through pipe 181, a port 84, valve 70 to the pipe 120. Similarly when magnet 81 is deenergized, a pipe 121, which is connected to pipes 122 and 123 in Fig. 3 is opened to atmosphere, and when magnet 81 is energized, pipe 121 is connected to reservoir 61.

In addition to the cab signal lights I provide a pressure gage 185, which is connected to pipe 121 to indicate the pressure therein.

20 Since the pressure in pipe 121 has a definite relation to the speed limit imposed upon the vehicle by the control magnet 81, the pressure gage may be calibrated empirically in terms of the permissive speed of the vehicle. 25 Not being connected to pipe 120, this pressure gage does not indicate the variations of speed limit imposed upon the vehicle due to the control effected by the action of magnet 80.

30 To explain the operation of this form of my train control apparatus, assume that a train of two or more cars, each of which is equipped with the apparatus shown in Figs. 1 and 2, travels along the track rails. Assume furthermore that all parts of the apparatus are in the positions shown in Fig. 1. That is, all relays are deenergized, consequently magnets 80 and 81 are deenergized, their circuits being broken at contacts 204 and 195 of relays 161 and 160 respectively. Hence, atmospheric pressure exists in pipes 120 and 121. For that reason the only force opposing the force exerted on diaphragm 341 due to the action of the centrifugal governor 4 is that exerted by spring 37. As a result the low speed limit of 10 miles per hour is imposed on the car or train as explained hereinbefore. The pressure gage 185 consequently indicates atmospheric pressure in pipe 121, which may be marked 10 miles per hour on the scale. Red lamp R is illuminated, its circuit being completed through the back contacts 205 and 196 of relays 161 and 160.

55 Assume now that the train encounters an energized ramp 109. As either contact shoe 162^a and 162^b of the first car of the train engages the ramp, alternating current will flow in the circuit for relay 158 of such first car, and the contacts of relay 158 will therefore become closed. Contact 189 of relay 158 closes the pick-up circuit of relay 160, which therefore becomes energized and closes its front contacts. As a result magnet 81 is energized, its circuit being closed

at front contact 195 of relay 160 and back contact 205 of relay 161, and in attracting its armature it opens lower valve 71 and closes upper valve 73 of double pin valve 69. Air pressure then enters pipe 121 from reservoir 61 and flows into reservoir 124 and cylinder 34 of Fig. 1, thereby imposing the "high speed" limit on the first car. The rise in pressure in pipe 121 is indicated by pressure gage 185. The circuit for green lamp G is closed through front contact 195 of relay 160 and back contact 205 of relay 161, so that a green light is displayed in the cab, the circuit for red lamp R being broken at contact 196 of relay 160.

80 Since as previously stated each car of the train is to be equipped with the speed control apparatus, it is desirable to apply the "high speed" limit to all cars of the train at once in order to permit the train to resume full speed, as soon as the first car passes over an energized ramp 109. That is, in order to permit the train to accelerate without delay, and in order that the cab signal and speed limit indicator on the first car will correctly indicate conditions on the entire train, it is desirable that the "high speed" control on the following cars be applied simultaneously with that on the first car, or in other words, that the relays 160 on each car of the train be energized at the same time the relay 160 of the first car is energized, due to the energization of relay 158 of the first car from an energized ramp 109. This is accomplished as follows:

95 When front contact 190 of relay 158 closes, battery 155 is connected to train wire 152 through the connection; from battery 155, wires 156, 150 and 197, contact 190 of relay 158 and wire 225 to wire 152, which by couplers 154 is made continuous through the length of the train. Then relay 160 on each car of the train becomes energized through the following circuit: from wire 152, through wire 225, back contact 194 of relay 160, energizing winding of relay 160, wires 192, 151 and 157 to battery 155. The contact finger 221 of each relay 160 is of such construction that front contact 193 closes before back contact 194 opens. As soon as front contact 193 is closed, relay 160 is held energized through the stick circuit traced hereinbefore. With relay 160 of every car energized, magnet 81 of each car is energized, hence, the high speed limit of 50 miles per hour is applied to the whole train.

100 Since the speed control equipment on each car of the train is identical, it is evident that if the ramp 109 is deenergized when passed by the first car and is energized at any time before it is passed by the last car of the train, the car whose contact shoe is in engagement with the ramp at the time it becomes energized will serve the function of the "first car" described in the preceding 110

paragraph, to simultaneously apply the "high speed" control on all cars of the train to permit an immediate acceleration to full speed. This is of great advantage in increasing the traffic capacity, as it permits a train which has been held down to a low speed due to unfavorable conditions ahead, to immediately resume full speed upon the closing of circuit controller P' due to the removal of the unfavorable condition provided some car of the train is in engagement with a ramp 109, and in fact permits continuous control of the train by circuits located in the roadway, without the employment of a continuous roadside contact rail, provided that the successive ramps 109 are spaced a distance apart not greater than the length of the train.

For another illustration of the operation of the above form of my system of train control, assume that the first car of the train next encounters a ramp 109 which has been deenergized by opening the corresponding switch P'. Then relay 158 is, of course, not energized, but the stick circuit of relay 160 is broken by circuit controller 164^a or 164^b. As a result relay 160 opens its front contacts, thereby breaking the energizing circuit of magnet 81 at contact 195. Consequently spring 83 closes lower valve 71 and opens upper valve 73 of double pin valve 69. Pipe 121 is therefore opened to atmosphere and the air pressure in cylinder 34 and reservoir 124 is exhausted through valve 73. Thus the force exerted against diaphragm 341 is gradually diminished and the speed limit is gradually decreased from 50 miles per hour to 10 miles per hour. This is indicated by gage 185. Green lamp G, the circuit of which is broken at front contact 195 of relay 160, is extinguished, and the red lamp R is illuminated because its circuit is closed by back contact 196 of relay 160.

In the case of a train of more than one car, this process is repeated for every car of the train as it passes the ramp 109.

Assume that the first car of the train next encounters an energized ramp 108. Contact shoe 163 engages this ramp causing alternating current to flow in the energizing circuit of relay 159, which circuit has been traced above so that the front contacts of this relay are closed. The pick-up circuit of relay 161 is then closed at contact 212 of relay 159, hence relay 161 closes its front contacts. Contact 204 of relay 161 closes the energizing circuit of magnet 80 which therefore attracts its armature and so opens lower valve 70 and closes upper valve 72 of double pin valve 68. Thus air pressure is admitted to pipe 120 from reservoir 61 and by exerting pressure against piston 36 in cylinder 34 of Fig. 1 it compresses spring 37. Piston 35 of cylinder 34 then presses against dia-

phragm 341 with a pressure corresponding to the medium speed limit. The circuit for red lamp R is broken at back contact 205 of relay 161 and the circuit for yellow lamp Y is closed at front contact 204 of relay 161. Consequently, the red light is extinguished and the yellow light is displayed.

Relay 159 also closes contact 222 to energize train wire 153 by the following circuit: from battery 155, wires 156, 150 and 197, contact 222 of relay 159, wire 223 to wire 75 153. By means of couplers 154, wire 153 of every car of the train is energized. Hence on each car of the train a circuit is completed from wire 153 to wire 223, back contact 203 of relay 161, winding of relay 161, wires 192, 151 and 157 to battery 155. Contact finger 232 of relay 161 is constructed so as to close the front contact 202 before it opens back contact 203, so that each relay 161 remains energized through its stick circuit once it has been energized. Thus magnet 80 on each car of the train is energized simultaneously, with magnet 80 on the first car. Similarly magnets 80 throughout the train will be energized simultaneously if ramp 108 is deenergized when passed by the first car of the train, but is energized by closing circuit controller P before it is passed by the last car of the train.

If now when magnets 80 are energized the first car of the train simultaneously encounters ramps 108 and 109 both of which are deenergized, or encounters a deenergized ramp 109 alone, neither relay 158 nor 159 will be energized but the stick circuit of relay 161 will be broken by circuit controller 164^a or 164^b and, as a result, relay 161 will become deenergized. Consequently, magnet 80 is deenergized, its circuit being broken at contact 204 of relay 161. Air pressure in pipe 120 and behind piston 36 of cylinder 34 is exhausted through upper valve 72 of double pin valve 68, allowing spring 37 to expand, with the result that the low speed limit is imposed on the car. The circuit for the yellow lamp Y is broken at contact 204 and the circuit for red lamp R is closed at contact 205 of relay 161. Hence the yellow light is extinguished and the red light is illuminated. This process is repeated by the apparatus on each car of the train as the contact shoes of each car encounter the deenergized ramps, hence the lowest speed limit is applied to each car of the train in succession.

Assume that as the train is proceeding under the "high speed" limit the first car of the train encounters ramps 108 and 109 of which ramp 108 is energized and ramp 109 is deenergized. Relay 159 is then energized by current from ramp 108, and closes the pick-up circuit of relay 161 at contact 212. Relay 161 opens at back contact 205 the circuit of red lamp R and closes at contact 204 the circuit for the yellow lamp Y 13c

and magnet 80 as described hereinbefore. Magnet 80 causes air pressure from cylinder 61 to enter pipe 120 leading to port 40 of cylinder 34, so that piston 36 is moved 5 to the left against stop 41. Circuit controller 164^a or 164^b opens the stick circuit of relay 160 which therefore breaks the circuit for magnet 81 at contact 195. As a result pipe 121 is opened to atmosphere at 10 valve 73 and the pressure in reservoir 124 and cylinder 34 gradually drops, so that the speed limit is gradually reduced from the high to the medium value and the yellow lamp Y is displayed. This process is re- 15 peated by the apparatus on each car of the train as the contact shoes of the several cars encounter the deenergized ramp 109 and the energized ramp 108, and as a result the speed limit is changed from the "high 20 speed" to the "medium speed" on each car of the train in succession.

Referring now to Fig. 2, I have here shown a modification of the apparatus of Fig. 1. This modification differs from the 25 apparatus of Fig. 1 in the following respects: Contact shoe 163 of Fig. 1, with its corresponding alternating current relay 159 and the medium speed control wire 153, are replaced by a contact 296 which is con- 30 trolled by air pressure acting on one side of a diaphragm 295 in opposition to a spring 293. Air pressure is brought to the under side of diaphragm 295 by means of a pipe 292 connected to the pipe 121 which 35 is connected to port 39 of cylinder 34 in Fig. 3. When the pressure in pipe 121 is at or above a certain value predetermined by the adjustment of spring 293, contact 296 is closed due to the upward displace- 40 ment of the diaphragm, but when the pressure falls below that value, contact 296 opens by virtue of the action of the spring. The pick-up circuit of relay 161 is passed through contact 296, so that this circuit is 45 as follows: from battery 155, through wires 156, 150, 197 and 298, contact 296, wire 297, relay 161, wires 192, 151 and 157 to battery 155. Hence the pick-up circuit of relay 161 is closed as long as air pressure 50 above the predetermined value exists in pipe 121. The circuit for red light R is: from battery 155 through wires 156, 150, 197 and 299, back contact 196 of relay 160, wire 300, back contact 205 of relay 161, wire 200, 55 lamp R, wires 192, 151 and 157 to battery 155. Hence red light R is illuminated when both relays 160 and 161 are deenergized. The circuit for yellow light Y and magnet 80 is: from battery 155, through wires 156, 60 150, 197 and 299, back contact 196 of relay 160, wire 300, front contact 204 of relay 161, wire 215, lamp Y and winding 80^a of the magnet 80 in multiple, wires 192, 151 and 157 to battery 155. Hence yellow light 65 Y is illuminated and magnet 80 is energized.

when relay 161 is energized and relay 160 is deenergized. The circuit for green light G and magnet 81 is: from battery 155, through wires 156, 150, 197 and 299, front contact 195 of relay 160, wire 202, lamp G 70 and winding 81^a of magnet 81 in multiple, wires 192, 151 and 157 to battery 155. Hence when relay 160 is energized green light G is illuminated and magnet 81 is energized.

When the apparatus shown in Fig. 2 is 75 used in connection with that shown in Fig. 3, the tension of spring 37 in Fig. 3, is such that it exerts no pressure against diaphragm 341 unless piston 35 is forced to the left by air pressure in pipe 120 or 121, so that if 80 the air pressure is exhausted from both of these pipes the brakes will be applied automatically if the train is run at even an extremely low speed. When the spring is compressed due to air pressure in pipe 120 the 85 speed limit is increased to a low value, as for example 10 miles per hour. Since the high speed limit is applied by the admission of air pressure through port 39 of cylinder 34, it remains the same as in the preceding cases.

To explain the operation of this modification of my system of train control, assume the apparatus is in the condition shown in Fig. 2, that is, that both relays 160 and 161 95 are energized. Then, as explained hereinbefore, green light G is illuminated, magnet 81 is energized and air pressure is admitted to pipe 121 and the adjoining passages so that the high speed limit is applied. Assume now that the train reaches a deenergized ramp 109, so that the stick circuits of relays 160 and 161 are broken at circuit controller 164^a or 164^b. Relay 160 becomes deenergized, but relay 161 remains energized, 105 its circuit being closed at the pneumatically controlled contact 296. As a result, yellow light Y becomes illuminated, magnet 80 becomes energized, and magnet 81 becomes deenergized. Therefore the air pressure in 110 pipe 121 gradually decreases and the speed limit is gradually reduced. Contact 296 opens as soon as the air pressure in pipe 121 drops below the predetermined value, but in the meantime the contact shoe has passed 115 off the ramp 109 so that the stick circuit for relay 161 is closed through the shoe operated contact whereby this relay remains energized. Piston 36 is moved against stop 41 due to air pressure in pipe 120, compressing 120 the spring 37, so that the train may proceed under the low speed limit of 10 miles per hour until a second ramp 109 is encountered. Assuming first that this ramp is deenergized, the stick circuit of relay 161 is opened 125 at contact 164^a or 164^b, and, contact 296 in the pick-up circuit of that relay being open, relay 161 becomes deenergized and opens at contact 204 the circuit for magnet 80 and yellow light Y. Air pressure is then ex- 130

hausted from pipe 120 and so releases spring 37. As explained hereinbefore, this causes the train to come to an absolute stop. Red light R is illuminated its circuit being closed at contact 205 of relay 161.

The train cannot proceed until it receives a "proceed" indication by the energization of the ramp 109 at which it came to a stop. When this ramp 109 becomes energized, relay 158 is energized and closes the circuit for relay 160 at contact 189. Relay 160 closes at contact 195 the circuits of green light G and magnet 80. Therefore the green light G is displayed, air pressure is admitted to pipes 121 and 122, and contact 296 is again closed; relay 161 then becomes energized and closes its contacts 202 and 204. Thus all the apparatus has been restored to the condition shown in Fig. 2, and the car or train may again proceed under the control of the "high speed" limit.

By this modification of my apparatus it will be noted that I obtain the equivalent of the three indications, proceed, caution, and stop by means of two consecutive engagements with similar ramps which are only capable of transmitting either one of two possible indications to the train.

Although I have herein shown and described only a few forms of apparatus embodying my invention, it is understood that various changes and modifications may be made therein within the scope of the appended claims without departing from the spirit and scope of my invention.

Having thus described my invention, what I claim is:

1. In combination, a railroad track, ramp rails along said track adapted to be energized, a vehicle adapted to travel on said track, a contact shoe on said vehicle for engaging said ramp rails, a relay on said vehicle adapted to be energized by current from said ramp rails, a stick relay on the vehicle, a pick-up circuit for said stick relay controlled by the first mentioned relay, a stick circuit for said stick relay controlled by a contact operated by the ramp rails, and speed controlling means on said vehicle controlled by the stick relay.

2. In combination, a railway track, high speed control and medium speed control ramp rails located adjacent said track and adapted to be energized, a train comprising a number of cars, a battery for each car, a high speed control wire continuous through the train, a medium speed control wire continuous through the train, a high speed control contact shoe for each car for engaging the high speed control ramp rails, a medium speed control contact shoe for each car for engaging the medium speed control ramp rails, a relay adapted to be energized by current from the high speed control ramp rails for controlling the energization of the high

speed control wire, a second relay adapted to be energized by current from the medium speed control ramp rail for controlling the energization of the medium speed control wire; a high speed control relay controlled by the first-mentioned relay, and provided with a holding circuit including a contact on said relay and a circuit controller operated by the ramp rails, said high speed control relay being provided also with a pick-up circuit including the high speed control wire; a medium speed control relay controlled by the second mentioned relay and provided with a holding circuit including a contact on the relay and the circuit controller operated by the ramp rails, and also provided with a pick-up circuit including the medium speed control wire, speed-controlling apparatus on each car adapted to give three indications, viz., high, intermediate and low speed; and high speed and medium speed control magnets for controlling speed controlling apparatus on the vehicle, said magnets being controlled by said high and medium speed control relays.

3. In combination, a railway track, ramp rails located adjacent said track and adapted to be energized, a train comprising a number of cars, a battery for each car, a control wire running the length of the train, a contact shoe for each car, a relay for each car adapted to be energized by current from a ramp rail, a circuit for each car controlled by said relay for energizing said control wire, a stick relay controlled by the first-mentioned relay, a stick circuit for the stick relay including a contact of said relay and a circuit controller operated by the ramp rails, a pick-up circuit for the stick relay including the control wire and a back contact of the stick relay, and speed controlling apparatus on each car controlled by the stick relay.

4. In combination, a railway track, ramp rails located adjacent said track and adapted to be energized, a train composed of a number of cars, a battery for each car, a battery wire for each car connected to the positive pole of the battery, a common wire for each car connected to the negative pole of the battery, a control wire for each car, couplings for connecting together corresponding wires of adjacent cars, a contact shoe for each car adapted to engage said ramp rails, a relay for each car adapted to be energized by current from each ramp rail, a stick relay for each car, a pick-up circuit for said relay controlled by the first-mentioned relay, a stick circuit for said stick relay controlled by a circuit controller operated by the ramp rails, means controlled by the first-mentioned relay for energizing the control wire, another pick-up circuit for said stick relay said circuit including the control wire and a back contact of the stick

relay, signals controlled by said stick relay, and an electromagnet controlled by said stick relay for controlling speed controlling means.

5. In combination, a railway track, ramp rails adapted to be energized located adjacent said track, a train composed of a number of cars, a battery for each car, a battery wire for each car connected to the positive pole of the battery, a common wire for each car connected to the negative pole of the battery, a control wire for each car, couplings for connecting together corresponding wires of adjacent cars, a contact shoe for each car adapted to engage said ramp rails, a ramp relay for each car adapted to be energized by current from the ramp rail, a stick relay for each car, a pick-up circuit for said stick relay controlled by the ramp relay, a stick circuit for said stick relay controlled by a circuit controller operated by the ramp rails, a circuit controlled by the ramp relay for energizing the control wire, another pick-up circuit for said stick relay said circuit including the control wire and a back contact of the stick relay, an electromagnet controlled by said stick relay for controlling speed controlling means on the train, a centrifugal governor operatively connected 30 to a wheel of said vehicle for controlling speed controlling means on said vehicle, a spring for opposing said governor, and means controlled by the electromagnet for giving the force exerted by said spring a plurality of values.

6. In combination, a railway track, ramp rails adjacent the track and adapted to be energized, a train comprising a plurality of similar cars for traveling on said track, a control wire extending through the train, a contact shoe for each car adapted to engage the ramp rails, a ramp relay for each car adapted to be energized by current from the ramp rails, a circuit for each car controlled by said relay for energizing the control wire, a high speed control relay, a pick-up circuit therefor controlled by the ramp relay, another pick-up circuit for the stick relay adapted to be energized by current from the control wire, a stick circuit for the stick relay comprising a circuit controller operated by the ramp rails, an electromagnet controlled by the high speed control relay for controlling speed controlling means for the train so as to permit one limit of speed, a contact controlled by said electromagnet, and a medium speed control relay controlled by said contact.

7. In combination, a railway track, ramp rails adjacent the track and adapted to be energized, a train comprising a plurality of cars, a control wire extending through the train, a contact shoe for each car adapted to engage the ramp rails, a relay for each car adapted to be energized by current from

the ramp rails, a circuit for each car controlled by said relay for energizing the control wire, a high speed control relay, a pick-up circuit therefor controlled by the first mentioned relay, another pick-up circuit therefor adapted to be energized by current from the control wire, a stick circuit therefor comprising a circuit controller operated by the ramp rails, speed controlling means on said vehicle capable of imposing a high speed limit, a low speed limit and an absolute stop on the train, an electromagnet adapted to control said speed controlling means so as to allow a high speed limit, a contact controlled through slow acting means by the electromagnet, a low speed limit relay controlled by said contact, a low speed control electromagnet for controlling said speed controlling means so as to impose a low speed limit on the train, said electromagnet being controlled by the above mentioned speed control relays, and a signal for each car controlled by the speed control relays.

8. In a system for protecting railway traffic, in combination; a railroad track; ramp rails located at intervals along said track; a train including a number of vehicles adapted to travel along said track; traffic protecting apparatus carried by said train; a relay associated with each vehicle for controlling said apparatus; a normally closed circuit for each relay; a circuit controller included in said circuit; a contact shoe carried by each vehicle and opening said circuit controller when engaged by one of said ramp rails; two insulated continuous conductors extending between said vehicles, said relays being electrically connected across said conductors only when deenergized; a source of current; electrically operable means associated with each vehicle and arranged to connect said source of current across said conductors when that means is energized; a partial energizing circuit for each of said means terminating at the wheels of the corresponding vehicle and at the corresponding contact shoe, and means for creating a difference of potential between each of said ramp rails and a track rail of said track.

9. In a system for protecting railway traffic, in combination; a railroad track; a train including a number of vehicles adapted to travel along said track; automatic traffic protecting apparatus carried by said train; a relay on each vehicle for controlling said apparatus; a normally closed circuit for governing each relay; a device carried by each vehicle and operable to interrupt the corresponding normally closed circuit; means located at intervals along said track for operating said devices; means controlled by said means for energizing the corresponding relay independently of the corresponding normally closed circuit; and

- means governed by each of said last mentioned means for energizing all of the other deenergized relays independently of their respective normally closed circuits.
- 5 10. In a system for protecting railway traffic, in combination: a railroad track; a train including a number of vehicles adapted to travel over said track; a relay on each of said vehicles, a circuit controller governed by said relay and open when said relay is energized; a pair of insulated conductors extending between said vehicle; electrical connections between each of said relays and said pair of conductors and including said circuit controller; a source of current; and means governed by devices located along said track for connecting said source of current with said pair of conductors.
- 15 20. 11. In a system for protecting railway traffic, in combination: a railroad track; a train including a number of vehicles adapted to travel over the track; a relay on each vehicle; a pair of continuous conductors extending between said vehicles; means for connecting each relay across said conductors when it is deenergized; and means for supplying current to said conductors.
- 25 30. 12. In a system for protecting railway traffic, in combination: a railroad track; a train including a number of vehicles adapted to travel over the track; a relay on each vehicle; a pair of continuous conductors extending between said vehicles; and a circuit adapted to connect each relay across said pair of conductors; a source of current; electrically operable means for connecting said source of current across said conductors; and traffic controlled impulse devices along the track and impulse devices on the train cooperating therewith for governing said electrically operable means.
- 35 40. 13. In combination, a train comprising a plurality of cars, a train governing magnet on each car, a holding circuit for each magnet including a normally closed contact adapted to be opened by trackway devices, a pick-up wire extending through the train for energizing each magnet when such wire is energized; and means on each car operable
- 45 50. 55 60. 65 70. 75 80. 85 90. 95
- by trackway devices for energizing said wire.
14. In an automatic train control system, a train including a number of vehicles each carrying a control device, electric conducting paths constituting a circuit for connecting said devices for simultaneous operation, and means comprising impulse elements along the track adapted to cooperate with impulse elements on the several vehicles, said means being adapted to cause energization of said circuit as a vehicle passes a trackway element dependent upon the existing condition of that element.
15. In combination, a railway vehicle, speed controlling apparatus thereon capable of three fixed conditions, devices located at intervals in the trackway and arranged for coöperation with said apparatus to cause said apparatus to change from the first to the second condition or from the second to the third condition, and slow acting means associated with said apparatus for causing gradual change from the first to the second condition whereby the influence of the trackway device which initiates such change is lost before the apparatus reaches the second condition so that the apparatus remains in the second condition until another deenergized trackway device is encountered.
16. In combination, a railway vehicle, apparatus thereon comprising two normally energized electromagnets, devices located at intervals in the trackway and arranged for coöperation with said apparatus to deenergize the first of said magnets, means controlled by said first magnet and rendered effective when the same is deenergized for causing the second of said magnets to be deenergized by the next trackway device which is encountered if such device is deenergized, and vehicle governing means controlled by said magnets.
- In testimony whereof I affix my signature in presence of two witnesses.
